SAFETY DEVICE FOR REFRIGERATING SYSTEMS

John Kirgan, Easton, Pa., assignor to Ingersoll-Rand Company, Jersey City, N. J., a corporation of New Jersey

Application December 19, 1934, Serial No. 758,182

3 Claims. (Cl. 62—152)

This invention is an improvement in safety devices, especially devices to insure the safe operation of machines in refrigerating systems which act to chill a quantity of water to be afterwards used for cooling purposes.

In refrigerating systems of this type, known as water-vapor refrigerating apparatus, the cooling effect is brought about by converting a part of the water into vapor and lowering the temperature of the main body of the water by the loss of heat which is extracted therefrom when said vapor is formed. To this end the water is introduced into a vessel or evaporator containing a high vacuum, and the water vapor formed is withdrawn by an evacuating member of sufficiently high capacity and transferred to a condenser where it is liquefied. To remove the water vapor from the evaporator a centrifugal compressor has been found to have many advantages, but such a compressor, to be of moderate dimensions and yet have the required capacity, must be operated at high speed, and the parts are therefore of comparatively light construction. Hence it is important that nothing but water vapor be allowed to enter the housing of the compressor, because if water in liquid form is admitted and gets into the path of the fast moving vanes thereof great damage such as the bending or breaking of the vanes will ensue before this condition can be remedied.

An object of my invention is to safe-guard the centrifugal compressor and prevent the admission thereto of water from the evaporator when the compressor is running. This is accomplished by means for quickly bringing the compressor to a stop when the danger of water in liquid form entering the compressor arises.

A further object of my invention is to control the operation of the evaporator and automatically overload the compressor in case the water level rises to a predetermined point where the entrance of water in liquid form to the compressor housing would begin, and at once slow down and quickly stop the latter. Hence, even if some water does enter the compressor, the rapid diminution in the speed thereof will effectually prevent any harmful consequences.

With these and other objects and advantages in view, the invention consists in the novel features set forth in the description, and pointed out in the claims. But the disclosure is illustrative only and changes may be made without exceeding the scope and broad meanings of the terms in which the appended claims are expressed.

The drawing shows in outline a centrifugal

compressor water-vapor refrigerating system with a safety device according to this invention.

The invention comprises an evaporator 1 to which the liquid refrigerant, such as water, is admitted by way of pipe 2. This pipe comprises a section which is disposed horizontally near the top of the evaporator and is there provided with a number of openings to enable the water to issue therefrom in the form of sprays or jets. At the top of the evaporator is an outlet 3 leading into the housing 4 of a centrifugal compressor, which extracts water vapor from the evaporator and delivers it to a condenser (not shown) to be liquefied. This compressor is driven by a motor such as an electric motor 5 connected to the rotor of the compressor by step-up gearing indicated in outline by the numeral 6. The compressor may embrace several stages, each with a set of revolving vanes on the compressor shaft operated by the motor 5. To run the motor, electric current is supplied from mains 7 to suitable connections including an overload switch or circuit-breaker 8.

The revolution of the rotor (not shown) in the compressor 4 at the start of the operation withdraws the gaseous and vapor contents of the evaporator 1 and creates therein a vacuum so that when water is admitted by the pipe 2 and sprayed downwardly into the evaporator 1, some of it is transformed into vapor at once and this vapor is exhausted by the compressor or rotary evacuator through the opening 3. The latent heat of vaporization that is absorbed by the part of the water which is vaporized, will lower the temperature of the rest of the water several degrees. The main body of the water remains liquid and flows out through an outlet opening 9 in the bottom of the evaporator to a discharge pipe 10 connected through a pump 11 to a delivery conduit which is connected to the outlet 12 of the pump. This conduit directs the water to the place where it produces the desired refrigerating effect. Then it flows back at a slightly higher temperature through the pipe 2 to the evaporator 1. In the supply pipe or conduit 2 within the evaporator 1 is a valve 13 having an arm extending outside of the pipe and controlled by a float lever 14. When the level of the water rises in the evaporator the float lever 14 tends to close the valve 13, and to open this valve when the water level sinks. Thus the admission of the water is regulated.

Owing to the fact that the pressure in the evaporator 1 is quite low the chilled liquid which collects on the bottom of the evaporator must be forcibly removed by the pump 11. So long as the pump 11 continues working or the valve 13 does

not get out of order, the water on the bottom of the evaporator does not become very deep and there is no risk of any of it reaching the top and passing through the outlet 3 into the housing 4 of the compressor. If, however, the pump fails to work or if the valve 13 gets out of order, the evaporator 1 may fill up with water, some of which will then enter the compressor, and in the compressor housing the rotating vanes of the compressor will collide with same. To prevent such an eventuality the top of the evaporator carries a pipe 15 projecting downward into the evaporator, and carrying at its inner end a relief valve 16 controlled by a float arm 17. Normally this float 5 will not be raised, but will hang in such a position as to close the valve 16. The upper or outer end of the pipe 15 opens through the bottom of an outside receptacle 18 which is on the top of the evaporator and normally contains enough water 10 to form a seal for the valve 16. The compressor 4 will have water or other suitable liquid seals at the bearings of the drive shaft of the compressor, so that the atmospheric air can not enter this housing around the drive shaft at its ends. Water 15 or other liquid flowing through these seals, or coming from any other source, can be discharged by way of a pipe 19 into the receptacle 18 and it is withdrawn from the receptacle 18 by pipe 20. Hence the receptacle 18 never overflows.

With this construction if the evaporator 1 by 20 any mischance ever fills with water, the float 17 will be lifted to open the valve 16 before any of the water can rise up to the compressor inlet 3, and as soon as the valve 16 opens the water in the vessel 18 quickly drains into the evaporator and enough air is then admitted through the inlet passage in the pipe 15 to destroy the vacuum therein. The admission of air, which is considerably heavier than water vapor, overloads the 25 compressor, and the speed of operation drops at once, so that even if the water in the evaporator rises and some of it gets into the compressor, no damage will result. The overloading of the compressor and its motor causes the switch to break the supply circuit of the motor, and then in a 30 moment or two, the compressor entirely stops.

After the compressor ceases to run, water might of course continue to be discharged from the pipe 2 and rise in the evaporator 1 until it passes up 35 through the outlet 3 into the compressor housing. As the vanes are now motionless, no ill effects will be produced, but before the system is again started, the water level has to be lowered in the evaporator 1 and all the liquid cleared out of the 40 compressor housing.

With this construction the system is safeguarded and all risk to the movable parts of the compressor is obviated. The arrangement is very simple and adapted to work instantly to give the desired result whenever an emergency arises.

5

If the liquid ever gets high enough to open the valve 16, to admit air, overload of the motor occurs at once and the motor is cut out. The density of the air acts as a brake and slows down the rotor of the compressor to a speed which will not wreck 10 or even damage the compressor should water enter the housing thereof.

I claim:—

1. The combination of an evaporator having connections to admit and discharge a liquid refrigerant, an evacuator to withdraw vapor of the refrigerant formed in the evaporator, means for supplying energy to operate the evacuator, said means comprising a cut-off device responsive to overload, and means controlled by conditions in the evaporator to bring about overloading of the evacuator and the energy-supplying means to cause actuation of said cut-off device and thereby render the evacuator inoperative.

2. The combination of an evaporator having connections to admit and discharge a liquid refrigerant, means normally acting to maintain constant refrigerant level in the evaporator, an evacuator to withdraw vapor of the refrigerant formed in the evaporator, means for supplying energy to operate the evacuator, said means comprising a cut-off device responsive to overload, and means arranged to be actuated when the first-named means fails to operate to bring about overloading of the evacuator and the energy-supplying means 35 and cause actuation of said cut-off device to stop the operation of the evacuator.

3. The combination of a chamber having a liquid inlet and outlet, a float-actuated valve controlling the inlet and normally acting to maintain 40 the liquid in the chamber at constant level, an evacuator creating vacuum in the chamber and removing vapor therefrom, means including a device responsive to overload and supplying energy to actuate the evacuator, normally-inoperative 45 means arranged to operate at abnormally high liquid level in the chamber to admit a medium heavier than said vapor to the evacuator, the medium upon admission acting to overload the evacuator and device to cut off the supply of energy and render the evacuator inoperative, and means providing a liquid seal for the normally-inoperative means.

JOHN KIRGAN.
